US00D617457S

(12) **United States Design Patent**
Baker

(10) **Patent No.:** **US D617,457 S**
(45) **Date of Patent:** **** Jun. 8, 2010**

(54) **MEDICAL INSTRUMENT**

(75) Inventor: **Jeff Baker**, Orlando, FL (US)

(73) Assignee: **Noble Marketing, Inc.**, Orlando, FL (US)

(**) Term: **14 Years**

(21) Appl. No.: **29/336,260**

(22) Filed: **Apr. 30, 2009**

(51) **LOC (9) Cl.** **24-02**

(52) **U.S. Cl.** **D24/137; D24/133**

(58) **Field of Classification Search** **D24/137, D24/150–151, 173, 138; D14/435.1, 358; D26/37, 39; 600/193, 194, 190, 178, 197, 600/200, 199, 557–558, 112, 182; 362/804, 362/172, 186; 439/144, 147, 529, 638**

See application file for complete search history.
